DESIGN FOR A NEGLIGEE

James N. Jebaily, New York, N. Y.

Application August 27, 1937, Serial No. 71,347

Term of patent 3½ years

To all whom it may concern:

Be it known that I, James N. Jebaily, a citizen of no country but of Syrian nativity and a French protégé, residing at New York city, in the county of Kings and State of New York, have invented a new, original, and ornamental Design for a Negligeé, of which the following is a specification, reference being had to the accompanying drawing forming part thereof.

Fig. 2 is a rear view of a negligeé embodying my new design.

The following features are characteristics of the negligeé shown in the drawing—a somewhat transparent openwork along the central front edges; the integral, central, front, bottom portion; and the fullness of the skirt at the top in the rear.

I claim:

The ornamental design for a negligeé, as shown and described.

JAMES N. JEBAILY.
